UNITED STATES PATENT OFFICE.

JAMES GRIMES, OF PORTSMOUTH, OHIO.

IMPROVEMENT IN FRUIT-CANS.

Specification forming part of Letters Patent No. 122,455, dated January 2, 1872.

To all whom it may concern:

Be it known that I, JAMES GRIMES, of Portsmouth, in the county of Scioto and State of Ohio, have invented a new and Improved Fruit-Can; and I do hereby declare the following to be a full, clear, and exact description of the same, reference being had to the accompany drawings forming part of this specification, in which—

Figure 1 is a vertical section of my improved fruit-can, showing its position before being sealed. Fig. 2 is a similar section of the can, showing its position after being sealed. Fig. 3 is an enlarged section of the sealed joint.

Similar letters of reference indicate corresponding parts in the several figures of the drawings.

My invention has for its object to improve the means for preserving fruit in cans; and to this end it consists in the construction of the can and its cover, as I will now proceed to describe.

In the accompanying drawings, A is a sheet-metal can, of the ordinary construction, with the exception of the upper edge, which is left of the usual thickness of the metal instead of being turned over or provided with a flange. B is the cover, struck up from one piece of sheet-metal with a depressed center, forming a square shoulder, c, to fit within the can mouth in close contact with its sides, an exterior groove or gutter, d, surrounding the top of the can opposite the shoulder C, and an exterior turned-up flange, e, to strengthen the cover outside the shoulder, and form an additional bearing or supporting surface for the can when sealed.

The process of sealing the can is as follows: It is first completely filled with the fruit to be preserved and the cover applied, as shown in Fig. 1, the shoulder c fitting tightly against the sides of the can, expanding them somewhat, and forming a close joint. The can is then reversed, as shown in Fig. 2, the whole weight of its contents resting upon the cover, while the edge of the can itself bears upon the metal outside the shoulder, as shown at f. If there is any defect in the body of the can which will cause it to leak, the liquid will ooze out into the gutter d, and the defect be thereby detected. If the can is found to be tight the gutter is filled with wax or other sealing material g, and the process is completed.

By constructing the cover B with the square shoulder c it fits tightly within the can, expanding its sides somewhat, and forming a close joint before the sealing material is applied. The exterior flange e strengthens the gutter and prevents the metal thereof from being bent inward or downward to displace the sealing material.

Having thus described my invention, what I claim is—

The sheet-metal fruit-can, consisting of the cylindrical body A and the cover B, the latter having the square shoulder c, the gutter d for sealing material, and the exterior strengthening and supporting flange e, as herein described, for the purpose specified.

Witnesses: JAMES GRIMES.

W.M. GRIMES,
WELLINGTON KINNEY.
